DAMPER CONTROL

Zoltan Roseman and Adolph Roth, Cleveland,
Ohio, assignors to Violet Roseman Saunt, Cleve-
land, Ohio

Application January 17, 1939, Serial No. 251,387

6 Claims. (Cl. 126—288)

This invention relates to dampers and particularly to adjustable dampers used in residential fireplaces.

The principal object of the invention is to provide an adjusting device for regulating the fireplace draft more conveniently and with more ease than is possible with the prior art devices.

Another object of the invention is to provide such device with a control lever that operates manually in a substantially straight line for a comparatively short distance.

A further object is to have the principal operating lever within easy reach of the user, where it may be seen and where it is out of the way of the flame, the heat and the soot of the grate.

Still another purpose of the invention is to construct an article of the class mentioned which when installed is not apt to come apart through ordinary operation.

These and other objects as well as a fuller understanding of the invention may be had by referring to the following description and claims together with the accompanying drawings in which like parts are designated by like reference characters, and in which:

Figure 1 is a side sectional view of the improved damper of this invention installed in a conventional fireplace;

Figure 2 is a vertical section taken along the lines 2—2 of the Figure 1;

Figure 3 is an enlarged sectional view of the damper unit alone showing the operating mechanism in greater detail;

Figure 4 is a front elevation of the operating mechanism taken along the lines and in the direction of the arrows 4—4 of the Figure 3;

Figure 5 is a sectional view taken along the lines and in the direction of the arrows 5—5 of the Figure 3;

Figure 6 is a sectional view of the hinge construction and assembly employed in this invention;

Figure 7 is a side view of the operating mechanism showing position of the parts when the damper is closed but about to be opened;

Figure 8 is a similar view showing the damper wide open;

Figure 9 is a view like that of Figure 8 except that the damper is shown as being locked in position;

Figure 10 is a similar view showing the damper unlocked and about to be closed;

Figure 11 shows the damper as being set in a partly open position;

Figure 12 is a side sectional view of a damper

installed in a conventional fireplace but showing a modified form of operating mechanism;

Figure 13 is a side view of the modified type of damper showing the damper locked in its open position;

Figure 14 is a front view of the operating mechanism taken along the lines and in the direction of the arrows 14—14 of the Figure 13; and

Figure 15 is a view similar to that of Figure 14 showing the operating mechanism unlocked and about to be closed.

The damper unit of this invention consists broadly of three main elements, namely: the dome or vault section, the movable plate member and the plate member actuating and setting device. Of this last element, there are two forms. The first form is designed for direct manual operation and the second form is intended to be used in connection with an auxiliary rod or a regular hooked fireplace poker.

The dome or vault section is made of substantial and durable cast metal. It consists of a rectangular plate 21 having a large opening in its central portion. The rectangular plate 21 is designed to be horizontally set and permanently built into a fireplace 22 just a little above the lintel 23 and in the chamber generally designated as the flue and which is indicated in the Figures 1 and 12 of the drawings by the character 24.

Extending laterally upward from and on the room side of the plate 21 and at an angle of about 45° is a heavy rigid wide plate 25. In the same manner but on the wall side of the plate 21 there projects upward a relatively narrower plate 26.

Two smaller and also rigid triangular side plates 27 extend upward and inward to connect the side edges of the plates 25 and 26 with the horizontal plate 21.

The narrow back plate 26 is provided with two small horizontal slots 28 quite close to and in line with the top edge thereof. The slots 28 are nearer to the side edges of the plate 26 than to its vertical center. The edges of the wide plate 25, of the narrow plate 26 and the two triangular side plates 27 form a vent which leads upward directly into the fireplace chimney 29. The opening thus formed is herein referred to as the chimney opening.

Angular back stops 30 are attached to the wall side of narrow plate 26 slightly below the top edge to prevent the movable plate member from opening up too far. The top portion of the stops 30 projects perpendicularly upward for about two

inches. The bottom portion is drilled to accommodate simple screws which engage the plate 26 a little below the horizontal slots 28.

The movable plate member consists of a flat 5 oblong metal plate 31 just large enough to close the chimney opening. It has attached to it or integral with its bottom horizontal edge, two curved tongues 32 which fit into and articulate within the slots 28.

10 The tongues 32 project inwardly at an angle from the plate 31; their bottom surfaces are concave and are provided with short tabs 33. The concave surfaces of the tongues move easily on the convex edges of the slots 28 as is shown in 15 the Figure 6. The tabs 33 prevent the plate 31 from accidentally becoming separated from the plate 26. In assembly, the two plates 26 and 31 are first linked together and then the stops 30 are screwed in place. The tongues 32 can only 20 be inserted or removed from the slots 28 when the stops 30 are not attached thereto.

Near the top edge of the movable plate 31 and on its inside surface there are two parallel U shaped metal guides 34 which form a track and a 25 channel for engagement with and the movement of the cam lever unit hereinafter described.

The movable plate member actuating and setting device of the preferred form and which is illustrated on the first two sheets of the drawings 30 consists of a stout metal bracket 41 firmly attached to the inside of the rear plate 26 with suitable bolts 42. Extending inward and upward from the bracket 41 are two parallel vertical lined arms 43. A suitable pivot 44 is secured between 35 the arms 43 on about a plane with the horizontal plate 21. Upward and a little to the inside a pin 45 is similarly fastened. The latter pin 45 serves to properly space and brace the arms 43 and also acts as a stop or detent for the ratchet 40 54 which will be described in detail later. Above the pivot 44 a second horizontal pivot 46 is similarly secured.

Connected to the second pivot 46 and extending substantially upward therefrom is the cam 45 lever 47 which engages and operates in the guide tracks 34 and channel 35 of the movable plate member. The cam lever 47 is solid or closed at its top 49 and bottom 52, but is slit or open at its mid-section so as to form a longitudinal channel 48. The top end 49 is slightly curved so as to fit between the two guide tracks 34 and is retained therein by the horizontal pin 51 which moves in the channel 35 as the plate 31 opens or closes. The bottom end 52 which plays on the pivot 46 is set between the arms 43 with friction or tension washers 53. These washers 53 tend to retain the cam lever 47 in the position desired but are not strong enough to hold the position for any great 50 length of time.

In order to hold the cam lever 47 in position without relying on the tension washers 53 a ratchet or pawl-bar 54 is pivotally attached to the lever 47. The pawl-bar 54 is curved; is loosely pivoted at its end 55 in the channel 48. The opposite serrated end 56 engages the detent 45 at different stations depending upon the position of the movable plate member. The end 55 of the pawl-bar 54 is slightly wider than the mid-section 70 of the cam lever 47; that is, the pawl-bar is pivoted in and extends outside on both sides of the channel 48 slightly. This projection is more clearly shown in the Figure 3 of the drawings. The serrated end of the pawl-bar 54 has a small lug 40 projecting from its top to prevent it from

moving too far and falling through the channel 48.

The operating lever or handle 57 is connected to the arms 43 close to its upper end and at the pivot 44. The top end of the handle 57, the portion above the pivot 44 is provided with two curved fingers 58 and 59. The inside or longer finger 58 is comparatively straight and moves between the arms 43 when the bottom end of the handle 57 is manipulated. It also, upon the pulling of the handle, raises the pawl-bar 54 so as to disengage the detent 45 and then it pushes the cam lever 47 outward thereby causing the plate 31 to open or to move toward its vertical position. The shorter and more curved finger 59 acts upon the pawl-bar 54 in substantially the same manner when the handle 57 is pushed outward, but it instead, presses upon the opposite side of the cam lever 47 and tends to close the plate 31 instead of opening it. The finger 58 touches the pawl-bar 54 above the pivot 46 while the finger 59 touches it below the pivot, so that upon either a pull or a push of the handle 57 the initial movement will disengage the teeth from the detent 45. Immediately upon reversing the movement of the handle 57 the pawl-bar 54 drops and locks the plate 31 in the position last set before the cam lever 47 has a chance to fall with it. The Figure 3 and all the figures on the drawings clearly show the principal steps and relative positions of the parts mentioned for opening and closing the damper.

The modified type of operating mechanism is very similar to the one previously described except that it makes use of a hooked rod or poker 35 78 for actuating the ratchet 73 instead of fingers.

A supporting bracket 61 having arms 62 is mounted on a rigid narrow plate 26. An operating lever 63 is swivelly connected to the arms 62 at the pivot 64. A slotted cam lever 65 is pivoted at its lower end 66 with a pin 67. The upper end 68 of the lever 65 is provided with a peg 69 for engagement with the guide tracks 34 and for movement in the channel 35 similar to that of the cam lever 47. The top end 68 of the cam lever 65 is made with a longitudinal slot 69 which slidably engages the small pin 70 on the top arm of the operating lever 63. A pulling of the bottom arm 71 of the lever 63 causes the slotted lever 65 to force the plate 31 outward and pushing on the same lever arm tends to close the movable plate member.

The lower arm 71 of the operating lever 63 has a comparatively long lateral slot 72 and between the slot 72 and the pivot 64 a ratchet 73 is pivoted. This ratchet 73 has a toothed or serrated end 74 which at various stations engages the detent 75 in accordance with the existing position of the plate 31 and there locks it in place. It has a finger 76 extending downward from the end engaging the pivot 77 which finger 76 moves adjacent to and across a lateral slot 72.

By inserting the hooked end of a poker 78 in the slot 72 and pulling thereon the plate 31 will tend to rise and open the damper. The finger 76 is then loose and the ratchet 73, because of the special angle at which the teeth 79 are cut, is free to move. However, when closing the damper the poker 78 is pressed against the finger 76 thereby raising the serrated end 74 and which initial movement unlocks the operating lever 63. The subsequent motion of the lever 63 sets the position of the plate 31. The various important steps of the opening and closing oper- 75

ations are shown in the Figures 12, 13 and 15 of the drawings.

As conducive to a better understanding and appreciation of this invention, attention must be called to modern residential building construction in which air conditioning and temperature insulation play an important part. It is particularly desirable to have such buildings free of uncontrolled draft and therefore a damper control that is highly efficient and which is easy and simple to adjust and comfortable and quick to operate is a necessity.

It will now be clear that there is provided by this invention a damper control which accomplishes the objects of the invention. While the invention has been described in specific forms and while certain general terms and specific language have been used, it is to be understood that the embodiment of the invention as described and shown is suggestive only and is not to be considered in a limiting sense. It is to be further understood that there are other forms or adaptations of the invention. For example, the bracket and arm members may be eliminated entirely. By making one of the side plates 27 perpendicular and by placing the guide tracks 34 on the plate 31 near such side plate 27, the movable parts herein mentioned may be pivoted directly on such side plates 27 and the ratchets 30 may be made to engage knobs or tabs projecting inwardly from the side plates 27. Such modifications and others which will suggest themselves to persons familiar with the art are all considered to be within the broad scope of the invention as no limitations upon it are intended other than those imposed thereon by the scope of the appended claims.

We claim:

1. A fireplace damper, comprising in combination, a stationary vault section having a chimney opening and adapted to engage a fireplace flue, a movable plate member fitting the chimney opening, a bracket member attached to the vault section, a cam lever mounted on the bracket member and actuating the movable plate member, a pawl-bar engaging the bracket member, and a hand lever mounted on the said bracket member for operating the said cam lever and actuating the said pawl-bar.
2. A fireplace damper, comprising in combination, a stationary vault section having a chimney opening and adapted to engage a fireplace flue, a movable plate member fitting the chimney opening, a cam lever mounted on the vault sec-

tion and engaging the movable plate, a pawl-bar pivoted on the lever and engageable with the vault section, a hand lever mounted on the vault section, and a means on the hand lever for simultaneously operating the said cam lever and actuating the pawl-bar.

3. A fireplace damper, comprising in combination, a stationary vault section having a chimney opening and adapted to engage a fireplace flue, a movable plate member having a cam thereon and fitting the chimney opening, a cam lever having a cam follower mounted on the vault section and engaging the said cam, a hand lever having means for operating the cam lever, and a means for temporarily setting the positions of the plate member and the cam lever.

4. A fireplace damper, comprising in combination, a stationary vault section having oblique sides one of the said sides having a chimney opening, a movable plate member hinged to the said open side and adapted to intercept the chimney opening, a bracket member attached to the open side, a cam device mounted on the movable plate member for swinging the said plate to various positions, a hand lever mounted on the bracket member for operating the cam device, and a means for temporarily setting the position of the plate member.

5. A fireplace damper, comprising in combination, a stationary vault section having oblique sides one of the said sides having a chimney opening, a movable plate member hinged to the said open side and adapted to intercept the chimney opening, a compound lever unit mounted on the vault section and engaging the movable plate member, a pawl member mounted on the lever unit engageable with the vault section and adapted to temporarily retain the movable plate member at the said chimney opening at various positions, and a means for operating the said plate member and for actuating the said pawl-bar.

6. A fireplace damper, comprising in combination, a stationary vault section, a movable plate member attached to the vault section, a compound lever unit mounted on the vault section and operative with the movable plate member, and a manipulating means engageable with and operating the compound lever unit the said manipulating means having a locking device thereon for temporarily setting the position of the said plate member.

ZOLTAN ROSEMAN.
ADOLPH ROTH.
